(57) **CLAIM**

The ornamental design for a tire, as shown and described.

DESCRIPTION

FIG. 1 is a perspective view of a tire showing my new design; FIG. 2 is a front view thereof, for which the rear view is the same;

FIG. 3 is a top view thereof, for which the bottom plan view is the same;

FIG. 4 is a right side view, for which the left side view is the same;

FIG. 5 is a cross-sectional view taken along line 5-5 in FIG. 2 and line 5'-5' in FIG. 4; and,

FIG. 6 is an enlarged view taken along lines 6-6 and 6'-6' in FIG. 2.

In the drawings, the broken lines showing portions of the peripheral boundary, sidewall and inner bead depict environment which forms no part of the claim.
